EXCAVATING MACHINE

Lewis M. Atkinson, Pittsburg, Kans.; C. O. Davis
administrator of said Lewis M. Atkinson, deceased

Application December 10, 1932, Serial No. 646,695

7 Claims. (Cl. 214—135)

The present invention relates to excavating machines and while particularly well adapted for use as a part of large revolving shovels, such as coal-stripping shovels; and shovels for the stripping and loading of ores, it is not limited to such use. It may be applied to the smaller excavating machines where the load or work is gathered by the use of a dipper, scoop, or similar unit adapted to penetrate the mass laterally in contradistinction to clam shell buckets which penetrate the mass by a direct fall or substantially vertical downward movement.

The principal object of the invention is to provide mechanism associated with the load hoisting mechanism to counteract the weight of, or the force of gravity acting upon the excavating member and accessories, and in some instances the load of material carried by the excavating member, so as to increase the efficiency and stability, and reduce the expense of operation of the equipment.

Another object of the invention is to provide counteracting mechanism associated with the load hoisting mechanism so as to reduce the horse power required by the prime movers, such as steam or internal combustion engines, or electric motors to operate the excavator, thereby increasing the dirt moving capacity of the excavator equipped with the present invention by utilizing power now lost in hoisting and lowering the excavating member and accessories. These parts of the excavating machine are heavier than the load to be lifted and by the use of the counteracting mechanism, the efficiency and capacity of the excavating machine are materially increased.

Another object of the invention is to utilize a vertically guided weight, preferably of a variable nature, much heavier than the parts of the load hoisting mechanism which it is to counteract, and by the use of motion transmitting and speed reducing mechanism operatively connected with the weight and load hoisting mechanism, provide optimum counteraction with but short lineal travel of the weight as compared with the lineal travel of the excavating member. This makes possible relatively short guides for the weight, reducing the cost of manufacture and increasing the stability of the structure on its base.

A further object of the invention is to provide means for adjusting the position of the weight in its guide, independently of movement of the excavating member. This is particularly advantageous where the excavating machine is equipped with a boom capable of being raised and lowered and where such change in position of the boom

effects the motion transmitting and speed reducing mechanism between the load hoisting mechanism and the weight. Such adjusting means also makes possible the use of relatively short guides for the weight since, by adjustment, its path of travel or amplitude of movement may be maintained substantially the same during a load engaging and lifting operation even tho the position of the boom be changed by raising or lowering same as required, according to the conditions met during different excavating operations. The adjusting means also enables the operator to take up stretch in the cables, which may form a part of the hoisting mechanism and the motion transmitting and speed reducing mechanism, which cables are lengthened as a result of normal wear. In a practical example, the motion transmitting and speed reducing mechanism may be plural-part tackle and by suspending the weight through two of such and utilizing the adjusting means for each, the weight may be suspended plumb in its guide instead of sagging on either side as a result of one weight supporting cable wearing faster, and hence lengthening to a greater degree, than the cable on the opposite side of the weight.

Another object of the invention is to provide counteracting mechanism which will serve its purpose as hereinbefore set forth and also aid in maintaining the stability of the machine, thereby avoiding the use of heavy ballast weight, now commonly used at the rear of the excavator cab opposite to the end supporting the boom, and which ballast, as now commonly used, serves but one purpose,—to offset the weight of the mass at the opposite side of the center of gravity of the machine.

A further object of the invention is to provide counteracting mechanism which may be applied to the conventional or now commonly used excavating machine without considerable change or replacement of parts.

Other objects and advantages of the invention will appear in the following detailed description, taken in connection with the accompanying drawings, forming a part of this specification, and in which drawings:

Figure 1 is a view partly in elevation and partly in vertical section showing an excavating machine equipped with one form of the present invention.

Figure 2 is a fragmentary view in plan, with parts broken away to show details.

Figure 3 is an end elevation of the machine, same having been swung on its base thru an arc

of ninety degrees from the position shown in Figure 1.

Figure 4 is a view on an enlarged scale, partly in elevation and partly in vertical section, showing the weight, a portion of the motion transmitting and speed reducing mechanism, and means for adjusting the latter so as to maintain the same path of travel for the weight, regardless of the position of the boom.

10 Figure 5 is a detail view in elevation showing a modification of such adjusting means.

Figure 6 is a view similar to Figure 1 showing a modification of the invention, and particularly well adapted for use as an addition to conventional or now commonly used excavating machine.

Figure 7 is a view similar to Figure 2 but showing the modification as disclosed in Figure 6.

In the drawings, wherein similar characters 20 designate similar or like parts throughout the several views, A designates a carriage of the excavating machine; B the revolving frame mounted thereon; C load collecting and hoisting mechanism on frame B and comprising a boom D, boom hoist E, load engaging unit or excavating member F, boom machinery G and excavator hoist H; and J counteracting mechanism associated with the load collecting and hoisting mechanism C, and comprising a weight K, a support 25 and guide L for the weight, motion transmitting and speed reducing mechanism M, and means N for adjusting the motion transmitting and speed reducing mechanism to change the relative position of the weight K in its guide, independently 30 of movement of the load engaging unit.

In the example shown, the carriage A comprises a base 8, supported by trucks 9.

The frame B may be revolutely mounted upon the base 8 in any suitable manner, so as to swing 40 about an upright axis. In the example shown, the frame is elongate in shape with the pivotal axis nearer the end 10 than the end 11, as is common practice.

While, in the example shown, the invention is applied to an excavating machine where the load 45 hoisting mechanism comprises a boom, having associated therewith an excavating member of the dipper type, having a dipper handle co-acting with boom machinery, it is to be understood that the invention may be applied to other types 50 of excavating machines and perhaps its only limitation is that it is not applicable to excavating machines using clam shell buckets intended to penetrate the mass to be lifted, by direct fall, or 55 a substantially vertical downward movement. The boom D is pivotally connected at its foot 12 to the end 10 of frame B, by brackets 13, a pivot pin 14 or other suitable assembly permitting the boom to be swung upwardly and downwardly by 60 use of the boom hoist E. The boom is provided with a sheave 15 at its point for cooperation with the excavator hoist H. The load engaging unit or excavating member F comprises a dipper 16 and a dipper handle 17, the latter being provided 65 with a rack 18 for cooperation with the boom machinery G. Such machinery, in the example shown, comprises a shipper shaft 19 having a pinion 20 thereon for meshing relation with the rack 18, the shipper shaft 19 being rotated 70 through gear 21 thereon, meshing with a pinion 22 on the shaft of motor 23. By this boom machinery, the excavating member F may be projected and retracted with respect to the boom in the usual manner.

75 In the example shown, the boom hoist E com-

prises four-part tackle 24 associated with a drum 25, operated in any suitable manner, such as by mechanism including worm 26 and worm wheel 27.

The excavator hoist H, in the example shown, 80 comprises a drum 28, rotated by a gear 29, meshing with a pinion 30 on the shaft 31 of prime movers 32, and suitable tackle 33 connecting the excavating member F with the drum. In the example shown, the prime movers 32 are 85 electric motors, suitable current being supplied thereto through motor-generator set 34. As a typical example, the drum 28 may be of the type provided with oppositely running grooves, starting at the center, so that two lines or cables are operatively connected to the drum, and to the dipper bail 36, the cables 35 running over boom point sheaves 15 in the usual way.

Concerning the counteracting mechanism J as 90 shown in Figures 1-5, the weight K is preferably in the form of a large receptacle 37 containing a quantity of material 38 of considerable weight, such as fragments of metal. The effective weight of the unit may therefore be varied by adding material to, or removing material from the receptacle 37. Thus optimum counteraction, utilizing the weight, may be had by experiment and observation of the equipment in operation. The weight 37 is preferably provided with oppositely 95 disposed grooves 39 for cooperation with rails 40 of the support L, these rails 40 providing a guideway 41 in which the weight moves. The support L comprises uprights 42, a cross beam 43, braces 44, extending upwardly and diagonally from the frame B to the beam 43, and tie members 45 connecting beam 43 with an A-frame 46, forming a part of the boom hoist E.

In the example shown, the motion transmitting and speed reducing mechanism M is in the 100 form of three-part tackle altho it is to be distinctly understood that this is merely by way of example, since other plural-part tackle may be used, or other mechanism associated with the hoisting mechanism and the weight, to move in unison, and so that the weight has less linear movement than the excavating member during a hoisting operation. As shown in Figures 1 and 2, the three-part tackle is duplicated adjacent opposite ends of the weight, and it suffices to 105 describe one thereof. In the form shown in Figures 1, 2, 3 and 4, the three-part tackle comprises a multiple sheave block 50 carried by support L; a sheave 51 secured to weight K; and, a cable 52 having its one end portion secured to 110 and adapted to be wound on the same drum 28, that forms a part of the load hoisting mechanism, and its other end portion secured, as at 53, to a projection 54 of block 55 which supports sheave 51. Thus there is a run 56 of cable, 115 from drum 28 to sheave block 50 which may be taken upon the drum 28, on the same surface thereof formerly occupied by the cable 35, as the dipper descends; a run 56' of cable between sheave block 50 and sheave 51; a run 57 of cable from sheave 51 back to sheave block 50; 120 and, a run 58 of cable from sheave block 50 to the point of attachment 53 to the weight. Looking at Figure 1, if the drum 28 is rotated counter-clockwise the dipper 16 will descend, and the weight K will ascend in its guideway 41. However, the linear movement of the weight K will 125 be considerably less than the dipper 16, because of this motion transmitting and speed reducing mechanism operatively connected to the load hoisting mechanism and the weight. The weight 130

K may be made many times greater than the excavating member and its load and in fact may be made sufficiently heavy to overbalance the dipper, dipper handle and load, if desired, so as to 5 reduce the horse power required at prime mover 32, during a hoisting operation, and to facilitate disengagement of the load from the mass during the initial operation of the load collecting and hoisting mechanism for accumulating the load in the dipper. By locating the weight K and support L at the end 11 of frame B, the weight assists in maintaining the stability of the excavating machine at the side of the axis of rotation of the frame on its base 8, opposite to the boom D, excavating member F, boom machinery G and those portions of the excavator hoist H as are to the side of said vertical axis 10 opposite end 11. By overbalancing the dipper, dipper handle and load, as above set out, important advantages are 15 gained. The weight K in the example shown being more than three times heavier than the dipper, dipper handle and load, effectively assists in maintaining the stability of the revolving frame B on the carriage A, and the carriage A on the ground. This is especially advantageous when the boom machinery G and the hoist H have been 20 operated to extend the dipper 16 remote from the boom D with the dipper handle 17 substantially horizontal, (as when dumping the load from the dipper) at which time there is a tendency to tip the machine in the direction of the dipper if there is not sufficient counteracting weight adjacent the end 11 of the frame B. If the machine is 25 electrically operated, as by use of the motors 32 and the motor-generator set 34, regeneration during the lowering of the dipper is eliminated, reducing the heating of the hoist motors and generators. In isolated places where the excavating 30 machine must be operated by an electrical power plant located in the immediate vicinity of the excavating operations, the power plant capacity need not be as great as where there is equipment which regenerates electricity during the lowering 35 of the dipper and is subjected to extreme peak loads for lifting and causing the dipper to penetrate the mass of material to be hoisted or moved. According to this embodiment of the present invention, the load peak during digging or penetration 40 of the dipper into the material to be dislodged and collected is reduced to a minimum. Assuming that it is desirable to change the position of the boom D, by moving it upwardly, the dipper and dipper handle remaining in the same 45 relative position to the boom as shown in Figure 5, the weight K will descend, since, in order to maintain this relative position of the dipper handle to the boom, it will be necessary to rotate drum 28, to take up the slack in cable 35. On 50 the other hand, if the boom D is to be lowered from the position shown in Figure 1, the dipper handle still retaining its same relative position to the boom, the weight K must be lifted, since drum 28 must be rotated to play out more cable 35 and this rotation of the drum lifts the weight 55 through mechanism M. For this, and other reasons, the means N is provided for adjusting the motion transmitting and speed reducing mechanism to change the relative position of the weight in its guideway 41, independently of movement 60 of the excavating member. This may be accomplished, as shown in Figure 4, by supporting the multiple sheave block 50 by a screw threaded shaft 60, extending through an opening 61 in beam 43, the shaft 60 receiving a nut 62, or a 65 wheel having an internally screw threaded hub, the shaft 60 having a swivel connection with block 50, as shown at 63. The nut 62 may engage a bearing 64 resting upon beam 43. Thus by rotating nut 62, the plural-part tackle may be bodily moved upwardly or downwardly, according to the direction of rotation of the nut, and the relative position of the weight K in its guideway changed, while the load hoisting mechanism remains inert. This device may also be used to take up line wear 70 and to make sure that the weight K is suspended plumb, as hereinbefore described. If desired the multiple sheave block 50 may be dispensed with, and single sheave blocks 70 provided as shown in Figure 5, each independently supported by a device N. This permits the blocks 70 to independently swivel on the shafts 60, for the sheave receiving the run 56 of cable is most likely to be subjected to wear, as the cable moves on and off the drum 28, this independent swiveling of the blocks, reducing wear to a minimum. 75 In the form of invention shown in Figures 6 and 7, the arrangement is similar to that shown in Figures 1-4, with the exception that the motion transmitting and speed reducing mechanism M has connection with the load hoisting mechanism C, at bail 36 of dipper 16, instead of to the drum 28 of the excavator hoist H. This makes necessary the use of another boom point sheave 80 for each run of cable 81 from the bail 36, over the sheave, to the multiple sheave block 50. In this example, while the weight K may be many times heavier than the dipper 16 and its handle 17, so as to assist in maintaining the stability of the excavating machine, it should not be made so 85 heavy as to overbalance the empty dipper and associated parts. In this form, if the boom D is raised or lowered, the dipper and its handle still retaining the same relative position to the boom D, the weight K is proportionately lowered or 90 raised, respectively, which emphasizes the importance of means N, otherwise it would be necessary to provide a much longer guideway 41 for the weight. 95 In the example shown, the invention has been applied to large revolving shovels, such as are 100 used for coal or ore stripping, that is, for removing the overburden, or for digging canals, but it is to be understood that the invention may be applied to smaller excavating machines, and 105 when so doing it may be desirable to support the weight K by motion transmitting and speed reducing mechanism operatively connected to the central portion of the weight, instead of 110 duplicating this mechanism with connections adjacent opposite ends of the weight. Other means than that comprising the shaft 16 and nut 62 may be utilized to adjust the weight in its guideway, independently of movement of the load engaging unit, or this means shown in Figure 4 115 may be connected between the block 55 and weight K, or the means may be provided at the beam 43, as well as at the weight, where the boom D is intended for considerable movement in a vertical plane. In actual reduction to practice I have found that the application of my invention to excavating machines materially increases the capacity of the machine for doing work, both as to load hoisted, and time required 120 for hoisting operations. As an example, an excavating machine equipped with two 250 H. P. 125 motors to operate the excavator hoist with a dipper having a capacity of 12 yards, successfully 130 operated a dipper of 18 yard capacity, after being 135 equipped with my invention. As another ex- 140 ample, an excavating machine equipped with two 145 150

ample, an excavating machine, having motors of a total of 500 H. P. capacity, formerly using a dipper of 16 yard capacity was equipped with one for 18 yard capacity after application of 5 my invention thereto, and with a faster hoisting speed, and a ten per cent saving in hoisting power.

In reduction to practice, it has been found that the forms of invention illustrated in the 10 drawings and referred to in the above description as practical embodiments of the invention, have been found efficient and practical; yet realizing that the conditions concurrent with the adoption of the mechanism will necessarily vary, 15 it is desired to emphasize the fact that various minor changes in details of construction, proportion and arrangement of parts may be resorted to, when required, without sacrificing any of the advantages of the invention as defined in 20 the appended claims.

I claim:

1. In an excavating machine, the combination with a frame, and load hoisting mechanism carried thereby, including, a boom pivotally carried 25 by the frame, a boom hoist for raising and lowering said boom, a load engaging unit, and a hoist for said load engaging unit including a hoist line having a running connection with the boom remote from the pivotal connection of the 30 boom with the frame, of mechanism to counteract the weight of the load engaging unit, comprising, a weight, a guide carried by the frame, motion transmitting and speed reducing mechanism operatively connecting a moving part of the load engaging unit hoist and said weight 35 to move in unison so that the weight has less linear movement than the load engaging unit during a hoisting operation, and means for adjusting said motion transmitting and reducing mechanism to change the relative position of 40 said weight in its guide, independently of movement of the load engaging unit, to compensate for a change in position of the boom relative to the frame.
2. In an excavating machine, the combination with a frame, and load hoisting mechanism carried thereby, including, a boom pivotally carried by the frame, a boom hoist for raising and lowering said boom, a load engaging unit, and a hoist 45 for said load engaging unit including a hoist line having a running connection with the boom remote from the pivotal connection of the boom with the frame, of mechanism to counteract the weight of the load engaging unit, comprising, a weight, a support carried by the frame and providing a guideway for the weight, plural-part tackle between the support and weight and suspending the weight in said guideway, said tackle operatively connected to a moving part of the load hoisting mechanism to move in unison 50 therewith and so that the weight has less linear movement than the load engaging unit during a hoisting operation, and means for adjusting the tackle to change the relative position of the weight in its guideway, independently of movement of the load engaging unit, to compensate for a change in position of the boom relative to the frame.
3. In an excavating machine, the combination with a frame, and load hoisting mechanism carried thereby, including, a boom pivotally carried by the frame, a boom hoist for raising and lowering said boom, a load engaging unit, and a hoist for said load engaging unit including a hoist line 55 having a running connection with the boom remote from the pivotal connection of the boom

with the frame, of mechanism to counteract the weight of the load engaging unit, comprising, a weight, a support carried by the frame and providing a guideway for the weight, plural-part tackle between the support and weight and suspending the weight in said guideway, said tackle operatively connected to a moving part of the load hoisting mechanism to move in unison therewith and so that the weight has less linear movement than the load engaging unit during a hoisting operation, and means for bodily moving the tackle and weight relative to the support.

4. In an excavating machine, the combination with a frame, a boom pivotally carried thereby, a boom hoist for raising and lowering said boom, a load engaging unit and a hoist for said load engaging unit carried by the frame and including a hoist line having a running connection with the boom remote from the pivotal connection of the boom with the frame, of mechanism to counteract the weight of the load engaging unit and its load, comprising, a weight, a guide carried by the frame, motion transmitting and speed reducing mechanism operatively connecting a moving part of the load engaging unit hoist and said weight 100 to move in unison so that the weight has less linear movement than the load engaging unit during a hoisting operation, and means for adjusting said motion transmitting and speed reducing mechanism to change the relative position 105 of said weight in its guide, independently of movement of the load engaging unit, to compensate for a change in position of the boom relative to the frame.

5. In an excavating machine, the combination with a frame, a boom pivotally carried thereby, a boom hoist for raising and lowering said boom, a load engaging unit, and a hoist for said load engaging unit carried by the frame and including a hoist line having a running connection with the boom remote from the pivotal connection of the boom with the frame, of mechanism to counteract the weight of the load engaging unit and its load, comprising, a weight, a guide carried by the frame, motion transmitting and speed reducing mechanism operatively connecting a moving part of the load engaging unit hoist and said weight 110 to move in unison so that the weight has less linear movement than the load engaging unit during a hoisting operation, and means for adjusting said motion transmitting and speed reducing mechanism to change the relative position 115 of said weight in its guide, independently of movement of the load engaging unit, to compensate for a change in position of the boom relative to the frame.

6. In an excavating machine, the combination with a frame, a boom pivotally carried thereby, a boom hoist for raising and lowering said boom, a load engaging unit, and a hoist for said load engaging unit carried by the frame and including a hoist line having a running connection with the boom remote from the pivotal connection of the boom with the frame, of mechanism to counteract the weight of the load engaging unit and its load, comprising, a weight, a support carried by the frame and providing a guideway for the weight, plural-part tackle between the support and weight and suspending the weight in said guideway, said tackle operatively connected to a moving part of the load hoisting mechanism to move in unison therewith and so that the weight has less linear movement than the load engaging unit during a hoisting operation, and means for adjusting the tackle to change the relative position of the weight in its guideway, independently of movement of the load engaging unit, to compensate for a change in position of the boom relative to the frame.

15 bodily moving the tackle and weight relative to the support.

7. In an excavating machine, the combination with a frame, and load hoisting mechanism carried thereby including a load engaging excavating member, of mechanism to counteract the weight of the said member comprising a support providing a vertical guideway, a weight movable in said guideway, motion transmitting and speed reducing mechanism operatively connecting a moving part of said load hoisting mechanism and said weight to move in unison so that the weight has less linear movement than the load engaging and

excavating member during a hoisting operation, said motion transmitting and speed reducing mechanism having connections with the weight adjacent opposite sides of the guideway, and means adjacent each side of the guideway for adjusting said motion transmitting and speed reducing mechanism to change the relative position of the weight vertically in the guideway and to change the position of the weight at one side of the guideway to a greater degree than at the other side thereof, independently of movement of the load engaging and excavating member.
